SHOPPING BAG

Shigeharu Kuroda, 1994-29 Oshikuma-cho,
Nara, Nara Prefecture, Japan

Filed Mar. 11, 1968, Ser. No. 10,910

Term of patent 14 years

Int. Cl. D3—02

U.S. Cl. D87—3

FIG. 1

FIG. 2

FIG. 3

FIG. 4

FIG. 5

FIG. 6

FIG. 1 is a front elevation of a shopping bag showing my new design;

FIG. 2 is a right side view thereof;

FIG. 3 is a cross-section thereof taken along line 3—3 of FIG. 1;

FIG. 4 is a top plan view thereof;

FIG. 5 is a bottom plan view thereof; and

FIG. 6 is a rear elevation thereof.

I claim:

The ornamental design for a shopping bag, as shown.
